UNITED STATES PATENT OFFICE.

CHARLOTTE ELIZABETH KENT, OF OSGOOD, MISSOURI.

CLOTH-FOLDING DEVICE.

Application filed June 14, 1924. Serial No. 720,143.

To all whom it may concern:

Be it known that I, CHARLOTTE E. KENT, a citizen of the United States, residing at Osgood, in the county of Sullivan and State 5 of Missouri, have invented certain new and useful Improvements in Cloth-Folding Devices, of which the following is a specification.

This invention relates to devices for folding strips of cloth and has as one of its objects to provide a device of extremely simple construction which may be moved in advance of an iron and which will automatically fold a strip of cloth properly associated with it, the fold being permanently formed or set by the iron.

Another object of the invention is to provide a device for the purpose stated to accommodate cloth strips of various 20 widths so that a strip of any selected width may be provided with two parallel folds at opposite sides of its longitudinal median line, thus forming a binding or trimming, or, if desired, the device may be employed 25 by passing a relatively wide strip through the device and initially folding the said strip, and then passing the folded strip through the device to form further folds, so that in this manner rug rags may be folded 30 and used in producing colonial braided rugs.

A further object of the invention is to provide a device for the purpose stated which will not require any particular attention on the part of the user, it being merely necessary to thread the strip to be 35 folded, through the device and then advance the device along the strip by the nose of the iron employed in pressing the folded strip, so that the folding operation may be accomplished expeditiously and at the same time 40 accurately.

In the accompanying drawing:

Figure 1 is a vertical longitudinal section- 45 al view through the device in use and disposed at one end against the nose of an iron;

Figure 2 is a top plan view of the device illustrating the manner in which the folds 50 are formed;

Figure 3 is a transverse sectional view taken substantially on the line 3-3 of Figure 2.

The device consists primarily of a plate 1 55 which may be of sheet metal or any other

material found suitable for the purpose and which preferably has the substantially oblong rectangular form shown in the drawings. The plate is formed at intervals throughout its length with slots 2 which are 60 of suitable dimensions and which extend transversely of the plate and in parallelism to one another, and from that end of the plate which is indicated by the numeral 3, the slots are of gradually increasing length 65 so that the slot of shortest length is located next adjacent the said end 3 of the plate while the slot of greatest length is located next adjacent the opposite end of the plate. Considering the end edge 3 of the plate as 70 the rear edge and the opposite end edge as the advancing edge, the plate is struck up, in advance of each of the slots 2, to provide a pair of spaced folding fingers indicated in general by the numeral 4. Each of said 75 fingers comprises a shank portion 5 which extends upwardly substantially at right angles from the plane of the plate 1, and a terminal portion 6 which projects inwardly substantially at right angles from the shank 80 portion 5. At this point it will be understood and particularly by reference to Figure 3 of the drawings, that the terminals 6 of the folding fingers 4 of each pair are presented toward each other and overlie the upper surface of the plate 1, the said terminals being spaced a suitable distance above the said upper face of the plate to accommodate the folds of cloth of any ordinary thickness. It will likewise be observed by reference to Figure 2 that the inwardly presented sides of the shanks 5 of the folding fingers 4 which are associated with each slot 2, are located in direct alinement with the 85 end walls of the respective slots in the direction of the length of the plate. 90

In the use of the device, the strip of cloth to be folded, which strip has been either cut straight or on the bias, is inserted at one end through that one of the slots 2, the length 100 of which slot most nearly approximates one-half the width of the strip of cloth, and the cloth is engaged beneath the associated pair of folding fingers 4 and the end of the cloth strip is drawn through the slot and beneath 105 the terminal portions 6 of the fingers until the said end of the cloth is positioned slightly beyond the rear edge 3 of the plate. This arrangement is effected upon the surface of an ironing board, and a pressing iron, indicated 110

in the drawing by the reference letter I, is placed at its nose end upon the projecting end of the strip and the iron is then advanced along the strip with its nose in engagement with the said edge 3 of the plate. The advancement of the iron will, of course, result in a corresponding advancement of the plate 1 and by holding the strip to the surface of the ironing board, at the portion over which the iron has passed, the strip will be held stationary and the plate 1 advanced along its length thus automatically forming two folds in the strip at opposite sides of the longitudinal median line thereof as clearly illustrated in Figure 2 of the drawing. As before stated, more than two folds may be formed in the strip by first threading the strip through one of the slots 2 to form the initial two folds as shown in Figure 2, and then after the strip has been folded in this manner throughout its length, the strips may be inserted through that one of the slots 2 which is of substantially one-half the length of the slot through which the strip was initially passed. In this manner a substantially four-ply strip is produced.

It will be evident from the foregoing that the invention is extremely simple in construction and may be stamped from sheet metal at an extremely low cost and that it automatically performs the folding operation efficiently and expeditiously.

Having thus described the invention, what is claimed as new is:

1. A cloth folding device comprising a plate formed with a transverse slot, and cloth guiding and folding fingers having shank portions projecting upwardly from the plate and terminal portions projecting inwardly toward each other, the said fingers being arranged in spaced relation and in advance of opposite ends of the slot, the inwardly presented sides of the shanks of the fingers being located in alignment with the respective end walls of the said slot. 35
2. A cloth folding device comprising a plate formed with a series of transverse slots extending in parallelism and of successively increasing length throughout the series from one end to the other, and cloth guiding and folding fingers upon the plate in advance of each respective slot. 40
3. A cloth folding device comprising a plate formed with a series of transverse slots extending in parallelism and of successively increasing length throughout the series from one end to the other, and cloth guiding and folding fingers upon the plate in advance of each respective slot, the said fingers being located substantially in alignment with the respective end walls of the respective slot. 45
5. A cloth folding device comprising a plate formed with a series of transverse slots extending in parallelism and of successively increasing length throughout the series from one end to the other, and cloth guiding and folding fingers upon the plate in advance of each respective slot, the said fingers being located substantially in alignment with the respective end walls of the respective slot. 50
6. A cloth folding device comprising a plate formed with a series of transverse slots extending in parallelism and of successively increasing length throughout the series from one end to the other, and cloth guiding and folding fingers upon the plate in advance of each respective slot, the said fingers being located substantially in alignment with the respective end walls of the respective slot. 55
7. A cloth folding device comprising a plate formed with a series of transverse slots extending in parallelism and of successively increasing length throughout the series from one end to the other, and cloth guiding and folding fingers upon the plate in advance of each respective slot, the said fingers being located substantially in alignment with the respective end walls of the respective slot. 60

In testimony whereof I affix my signature.
CHARLOTTE ELIZABETH KENT. [L.S.]
